UNITED STATES PATENT OFFICE.

GEORGE F. EISENBROWN, OF READING, PENNSYLVANIA.

DESIGN FOR A TOMBSTONE.

56,277.

Specification for Design.

Patented Sept. 14, 1920.

Application filed April 6, 1920. Serial No. 371,769. Term of patent 3½ years.

To all whom it may concern:

Be it known that I, GEORGE F. EISENBROWN, a citizen of the United States, residing at Reading, in the county of Berks and State of Pennsylvania, have invented a new, original, and ornamental Design for a Tombstones, of which the following is a specification, reference being had to the accompanying drawing, forming a part thereof.

In the drawing:

The figure represents a front, elevational view of my new design.

I claim:

The ornamental design for a tombstone as shown.

GEORGE F. EISENBROWN. [L. S.]
